CROUSE-HINDS COMPANY, OF SYRACUSE, NEW YORK, A CORPORATION OF NEW
YORK.

ELECTRICAL COUPLING.

1,071,617.

Specification of Letters Patent. Patented Aug. 26, 1913.

Application filed May 2, 1910. Serial No. 558,757.

To all whom it may concern:

Be it known that we, JESSE L. HINDS and JOHN J. DOSSERT, of Syracuse, in the county of Onondaga and State of New York, have invented a certain new and useful Electrical Coupling, of which the following is a specification:

Our invention has for its object the production of an electrical coupling or line tapper, which is particularly simple in construction and highly efficient in use; and it consists in the combinations and constructions hereinafter set forth and claimed.

In describing this invention, reference is had to the accompanying drawing, in which like characters designate corresponding parts in all the views.

Figure 1 is a longitudinal sectional view, partly in elevation, of this coupling or line tapper, contiguous portions of conductors being also shown. Fig. 2 is a vertical sectional view taken at a right angle to Fig. 1, parts being omitted. Fig. 3 is a side elevation of this coupling, the movable division of the sleeve or band member being shown in its open position.

This coupling comprises generally a body or main member which normally supports or carries the remaining parts of the coupling, including parts movable relatively thereto, and includes a threaded stem and a transversely extending sleeve or band member at one end of the stem, a movable clamping element carried by the stem, and having a head located within the bore of the sleeve member, and a nut turning on the stem and coacting with the movable division of the sleeve member and with the clamping element.

1 is the threaded stem of the body of the coupling, and 2 and 3 are divisions of the sleeve or band member located at one end of the stem and adapted to receive a conductor 4, the division 2 being secured to the stem 1 and the division 3 being hinged at 5 to the division 2. The body of the coupling is also provided at its other end with attaching means for connecting the coupling to another object, as a second conductor 6, said attaching means including a contractile sleeve 7 arranged in a socket 8 opening from said other

end of the body, the sleeve 7 having a conical periphery which engages a complementary circumferential wall of the socket 8. The sleeve 7 is forced into the socket 8, by means of a nut or internally threaded sleeve 9 turning on said other end of the body and having an internal flange 10 which engages the outer end of the sleeve 7 and thereby forces said sleeve into the conical socket 8 and compresses the same upon the conductor 6. The portions of the stem adjoining the sleeve member include two part-cylindrical sections 11 and 12 complementary to each other and connected respectively to the divisions 2 and 3 of the sleeve member, one section as 11 being permanently fixed to the major part of the stem, and the other, 12 being separable therefrom and carried by the hinged division 3 of the sleeve member.

13 is the head of the movable clamping element which also includes a shank 14, the head 13 being located in the bore of the sleeve member and provided with an arcuate face 15 for engaging the conductor 4. The shank 14 extends into an axial passage 16 provided in the stem and preferably in the section 11 thereof and opening through the end face of such section into the bore of the sleeve member. The clamping element also includes lugs 17 which extend parallel to the shank 14, depend from the ends of the head 13 and slide in recesses 18 formed in the meeting faces of the sections 11 and 12, and project laterally on opposite sides of the stem and the sections thereof, these recesses 18 opening through the peripheries of the sections and also into the bore of the sleeve member. The recesses 18 are preferably of less length than the sections 11 and 12 and provided at their ends with shoulders 19, normally engaged by the ends of the lugs 17. Usually, the fixed section of the stem is formed with a part-cylindrical portion 20 concentric with, but of opposite curvature to, and of less radius than, the threaded surface of said fixed section 11, the axial passage 16 being formed partly in said portion 20, and the separable section 12 is formed with a recess 21 fitting said part-cylindrical portion 20.

22 is a nut turning on the threaded stem

and the sections 11 and 12 thereof against the projecting portions of the lugs 17 for forcing the clamping element axially of the stem and thus firmly clamping the conductor 4 in the sleeve member.

The hinge pin 5 connecting the divisions 2 and 3 of the sleeve member is located at one side of the path of movement of the head 13 of the clamping element in order that said element may be easily inserted and removed, but in order to prevent accidental removal of said element when the hinged division 3 is in its outward position as shown in Fig. 3, the hinge is provided with means, as a part 23 fixed to the division 3 and movable into the path of the head 13, and the entire length of said element including its stem and head is greater than the distance from the end face of the section 11 to the hinge pin 5. When the movable parts of the coupling are in their normal position as shown in Fig. 2, the contiguous surfaces 24, and 25 of the hinged division 3 and the fixed section of the stem are continuous so that the upper portion of the head 13 can be moved outwardly beyond the hinge pin 5, and thus upon the opening of the hinged division 3, the clamping element can be moved farther outwardly until the shank 4 is disengaged from the stem, but when the division 3 is swung outwardly and the clamping element is in its normal position, the part 23 associated with the hinged division 3 projects into the path of the head 13 of the clamping element and thus prevents outward movement of the clamping element far enough to disengage the shank 14 thereof from the stem 1 of the coupling.

What we claim is:—

1. In an electrical coupling, a body including a threaded stem and a transversely extending sleeve or band member carried by the stem, a clamping element movable relatively to the stem and the sleeve member and having a head located within the bore of the sleeve member and means slidably engaged with the stem and detachable therefrom, and a nut turning on the stem and coacting with the clamping element, said clamping element being removable from the stem while the nut is engaged with said stem, substantially as and for the purpose described.

2. In an electrical coupling, a body including a threaded stem and a transversely extending sleeve or band member comprising two divisions, one being secured to a portion of the stem and the other being hinged to the former division and movable on its hinge for attaching the coupling to, or detaching the same from, an electric conductor, a clamping element movable relatively to the stem and the sleeve member and having a head located within the bore

of the sleeve member and means slidably engaged with the stem and detachable therefrom, and a nut turning on the stem and coacting with the hinged division of the sleeve member and with the clamping element, said clamping element being removable from the stem while the nut is engaged with said stem, substantially as and for the purpose specified.

3. In an electrical coupling, a body including a threaded stem and a transversely extending sleeve or band member comprising two divisions, one being secured to a portion of the stem and the other being hinged to the former division and movable on its hinge for attaching the coupling to, or detaching the same from, an electric conductor, a clamping element movable relatively to the stem and the sleeve member and having a head located within the bore of the sleeve member and means slidably engaged with the stem and detachable therefrom, means mounted on the body and movable into the path of the clamping element when being removed for holding said element from detachment when the movable division of the sleeve member is swung outwardly on its hinge, and a nut turning on the stem and coacting with the clamping element, substantially as and for the purpose set forth.

4. In an electrical coupling, a body including a threaded stem and a transversely extending sleeve or band member comprising two divisions, one being secured to a portion of the stem and the other being hinged to the former division and movable on its hinge for attaching the coupling to, or detaching the same from, an electric conductor, a clamping element movable relatively to the stem and the sleeve member and having a head located within the bore of the sleeve member and means slidably engaged with the stem and detachable therefrom, means associated with the hinge connecting the divisions of the sleeve member and movable into the path of the clamping element when being removed, for holding said element from detachment when the movable division of the sleeve member is swung outwardly on its hinge, and a nut turning on the stem and coacting with the hinged division and with the clamping element, substantially as and for the purpose described.

5. In an electrical coupling, a body including a threaded stem and a transversely extending sleeve or band member comprising two divisions, one being secured to a portion of the stem and the other being hinged to the former division and movable on its hinge for attaching the coupling to, or detaching the same from, an electric conductor, a movable clamping element having a head located within the bore of the sleeve

member and means slidably engaged with the stem and detachable therefrom, the hinge connecting the divisions being located at one side of the path of the clamping element and having a part movable into the path of said element when the hinged division is swung outwardly on its hinge, said part preventing the detachment of the clamping element from the stem and the sleeve member, and a nut turning on the stem and coacting with the hinged division and with the clamping element, substantially as and for the purpose specified.

6. In an electrical coupling, a body including a threaded stem and a transversely extending sleeve or band member comprising two divisions, one being secured to a portion of the stem and the other being hinged to the former division and movable on its hinge for attaching the coupling to, or detaching the same from, an electric conductor, the stem having an end face contiguous to the bore of the sleeve member, a movable clamping element having a head located within the bore of the sleeve member and means extending lengthwise of, and slidably engaging the stem, the length of the clamping element being greater than the distance between said end face of the stem and the hinge connecting the divisions of the sleeve member, and said hinge being provided with a part movable into the path of the clamping element when the movable division of the sleeve member is swung outwardly on its hinge, and a nut turning on the stem and coacting with the hinged division and with the clamping element, substantially as and for the purpose set forth.

7. In an electrical coupling, a body including a threaded stem and a transversely extending sleeve or band member comprising two divisions, one being secured to a portion of the stem and the other being hinged to the former division and movable on its hinge for attaching the coupling to, or detaching the same from, an electric conductor, a movable clamping element having a head located within the bore of the sleeve member and means slidably engaged with the stem and detachable therefrom, the hinged division being provided with a part normally arranged at one side of the path of movement of the clamping element and movable into said path when such movable division is swung outwardly on its hinge, thereby preventing detachment of the clamping element, and a nut turning on the stem and coacting with the hinged division and with the clamping element, substantially as and for the purpose described.

8. In an electrical coupling, a body including a threaded stem having attaching means for connecting the coupling to another object and a transversely extending

sleeve or band member carried by the stem, 65 said stem being provided with a lengthwise passage opening into the bore of the sleeve member, a clamping element movable relatively to the stem and the sleeve member and having a head located within the bore 70 of the sleeve member and a shank movable in the passage of the stem, and a nut turning on the stem and coacting with the clamping element, substantially as and for the purpose specified.

9. In an electrical coupling, a body including a threaded stem having attaching means for connecting the coupling to another object and a transversely extending sleeve or band member carried by the stem, 80 said stem being provided with a lengthwise passage opening into the bore of the sleeve member and with lengthwise recesses in opposite sides of the stem, a clamping element movable relatively to the stem and the 85 sleeve member and having a head located within the bore of the sleeve member, a shank slideable in the passage of the stem, and lugs extending into said recesses and projecting laterally beyond the periphery 90 of the stem, and a nut turning on the stem and shouldering against the projecting portions of said lugs, substantially as and for the purpose set forth.

10. In an electrical coupling, a body including a threaded stem and a transversely extending sleeve or band member comprising two divisions, one being secured to a portion of the stem and the other being hinged to the former division, said stem being provided with a lengthwise passage opening through an end face thereof into the bore of the sleeve member, a movable clamping element having a head located within the bore of the sleeve member and a shank movable in the passage of the stem, the hinge connecting the divisions of the sleeve member being located at one side of the path of the head of the clamping element, and the length of said element being greater than the distance from said end face of the stem to the hinge, and said hinge being provided with a part movable into the path of the head when the hinged division is swung outwardly, and a nut turning on the stem and coacting with the hinged division and with the clamping element, substantially as and for the purpose described.

11. In an electrical coupling, a body including a threaded stem and a transversely extending sleeve or band member comprising two divisions, one being secured to a portion of the stem and the other being hinged to the former division, said stem being provided with a lengthwise passage 120 opening through an end face thereof and with lengthwise peripheral recesses in opposite sides of the stem, the passage and the

- recesses opening into the bore of the sleeve member, a movable clamping element having a head located within the bore of the sleeve member, a shank movable in the passage of the stem, and lugs slideable in said recesses, the lugs projecting laterally beyond the periphery of the stem, the hinge connecting the divisions of the sleeve member being located at one side of the path of the head 5 of the clamping element, and the length of said element being greater than the distance from said end face of the stem to the hinge, and said hinge being provided with a part movable into the path of the head when the 10 hinged division is swung outwardly; and a nut turning on the stem against the projecting portions of the lugs and coacting with the hinged division, substantially as and for the purpose specified.
12. In an electrical coupling, a body including a threaded stem and a transversely extending sleeve or band member comprising two divisions, one being secured to a portion of the stem and the other being 15 hinged to the former division and movable on its hinge for attaching the coupling to, or detaching the same from, an electric conductor, said stem being provided with a lengthwise passage opening through one end 20 face thereof and with lengthwise peripheral recesses in opposite sides of the stem, the passage and the recesses opening into the bore of the sleeve member, a movable clamping element having a head located within 25 the bore of the sleeve member, a shank movable in the passage of the stem, and lugs slideable in said recesses, the lugs projecting laterally beyond the periphery of the stem, the length of said element being greater than 30 the distance from said end face of the stem to the hinge connecting the divisions of the sleeve member, and the hinged division of 35 said sleeve member being provided with a part normally arranged at one side of the path of movement of the head of the clamping element and movable into said path when such movable division is swung outwardly on its hinge and thereby preventing 40 detachment of the clamping element, and a 45 nut turning on the stem and coacting with said hinged division and with the clamping element, substantially as and for the purpose set forth.
13. In an electrical coupling, a body including a threaded stem having attaching means for connecting the coupling to another object and a transversely extending sleeve or band member at one end of the stem, portions of the stem adjoining the 55 sleeve member comprising two part-cylindrical sections complementary to each other, one being separable from the other which is rigid with the major part of the stem, and the portion of the sleeve member contiguous to said separable section being movable therewith, a clamping element movable relatively to the stem and the sleeve member and having a head located within the bore of the sleeve member and a nut turning on the stem and the sections thereof and coacting with the clamping element, substantially as and for the purpose described.
14. In an electrical coupling, a body including a threaded stem having attaching means for connecting the coupling to another object and a transversely extending sleeve or band member at the other end of the stem, the portions of the stem adjoining the sleeve member comprising two part-cylindrical sections complementary to each other, one being separable from the other which is rigid with the major part of the stem, and the portion of the sleeve member contiguous to said separable section being movable therewith, a clamping element movable relatively to the stem and the sleeve member and having a head located within the bore of the sleeve member, and a nut turning on the stem and the sections thereof and coacting with the clamping element, substantially as and for the purpose specified.
15. In an electrical coupling, a body for normally supporting parts of the coupling movable relatively thereto and including a threaded stem having attaching means for connecting the coupling to another object and a transversely extending sleeve or band member at one end of the stem, the portions of the stem adjoining the sleeve member comprising two part-cylindrical sections complementary to each other, one being separable from the other which is rigid with the major part of the stem and one being formed with lengthwise recesses opening through the periphery thereof and into the bore of the sleeve member, and the portion of the sleeve member contiguous to said separable section being movable therewith, a clamping element movable relatively to the stem and the sleeve member and having a head located within the bore of the sleeve member and also having lugs extending into the recesses and projecting on opposite sides of the stem, and a nut turning on the stem and the sections thereof and coacting with the projecting portions of the lugs, substantially as and for the purpose set forth.
16. In an electrical coupling, a body including a threaded stem having attaching means for connecting the coupling to another object and a transversely extending sleeve or band member at the other end of the stem, the portions of the stem adjoining the sleeve member comprising two part-cylindrical sections complementary to each

- other, one being separable from the other which is rigid with the major part of the stem, said sections being formed with lengthwise recesses in their meeting faces, 5 the recesses opening through the threaded peripheries of the sections and into the bore of the sleeve member, and the portion of the sleeve member contiguous to said separable section being movable therewith, a clamp- 10 ing element movable relatively to the stem and the sleeve member and having a head located within the bore of the sleeve member and also having lugs extending into the recesses and projecting on opposite sides of 15 the stem, and a nut turning on the stem and the sections thereof and coacting with the projecting portions of the lugs, substantially as and for the purpose described.
17. In an electrical coupling, a body for 20 normally supporting parts of the coupling movable relatively thereto and including a threaded stem having attaching means for connecting the coupling to another object and a transversely extending sleeve or band 25 member at the other end of the stem, the portions of the stem adjoining the sleeve member comprising two part-cylindrical sections complementary to each other, one being separable from the other which is rigid 30 with the major part of the stem, said sections being formed with lengthwise recesses in their meeting faces, the recesses opening through the threaded peripheries of the sections and into the bore of the sleeve member, 35 said recesses being of less length than the sections and thereby forming shoulders, and the portion of the sleeve member contiguous to said separable section being movable therewith, a clamping element movable relatively to the stem and the sleeve member 40 and having a head located within the bore of the sleeve member and also having lugs extending into the recesses and normally resting on the shoulders, the lugs projecting laterally on opposite sides of the stem, and a nut turning on the stem and the sections 45 thereof against the projecting portions of the lugs, substantially as and for the purpose specified.
- 50 18. In an electrical coupling, a body including a threaded stem and a transversely extending sleeve or band member at one end of the stem, the portions of the stem adjoining the sleeve member comprising two part- 55 cylindrical sections complementary to each other, one being separable from the other, the stem being provided with a lengthwise passage opening through the end of one of the sections into the bore of the sleeve member, and the portion of the sleeve member contiguous to said separable section being movable therewith, a movable clamping element having a head located within the 60
- bore of the sleeve member and a shank movable in said passage, and a nut turning on the stem and the sections thereof and coacting with the clamping element, substantially as and for the purpose set forth. 65
19. In an electrical coupling, a body including a threaded stem and a transversely extending sleeve or band member at one end of the stem, the portions of the stem adjoining the sleeve member comprising two part-cylindrical sections complementary to each other, one being separable from the other, and one being formed with lengthwise recesses on opposite sides thereof opening through its periphery and into the bore of the sleeve member, the stem being provided with a lengthwise passage 70 opening through the end of one of the sections and into the bore of the sleeve member, and the portion of the sleeve member contiguous to said separable section being movable therewith, a movable clamping element 75 having a head located within the bore of the sleeve member, a shank movable in said passage and lugs extending into the recesses and projecting laterally on opposite sides of the stem, and a nut turning on the stem and the sections thereof against the projecting portions of the lugs, substantially as and for the purpose specified. 80
20. In an electrical coupling, a body including a threaded stem and a transversely extending sleeve or band member at one end of the stem, the portions of the stem adjoining the sleeve member comprising two part-cylindrical sections complementary to each other, one being separable from the other, said sections being formed with lengthwise recesses in their meeting faces opening through the peripheries of such sections and into the bore of the sleeve member, the stem being provided with a lengthwise passage opening through the end of one of the sections and into the bore of the sleeve member, and the portion of the sleeve member contiguous to said separable section being movable therewith, a movable clamping element having a head located within the bore of the sleeve member, a shank movable in said passage and lugs extending into the recesses and projecting laterally beyond the stem, and a nut turning on the stem and the sections thereof against the projecting portions of the lugs, substantially as and for the purpose specified. 95
21. In an electrical coupling, a body including a threaded stem and a transversely extending sleeve or band member at one end of the stem, the portions of the stem adjoining the sleeve member comprising two part-cylindrical sections complementary to each other, one being separable from the other, said sections being formed with 100

lengthwise recesses in their meeting faces opening through the peripheries of such sections into the bore of the sleeve member, and the sleeve member comprising two divisions, 5 one being secured to one of the stem sections and the other being hinged to the former division and movable on its hinge with the other stem section for attaching the coupling to, or detaching the same from, an 10 electric conductor, the stem being provided with a lengthwise passage opening through the end of one of the sections and into the bore of the sleeve member, a movable clamping element having a head located within 15 the bore of the sleeve member, a shank movable in the passage of the stem and lugs 20 slidable in said recesses, the lugs projecting laterally beyond the periphery of the stem, the length of said element being greater 25 than the distance from said end face of the stem to the hinge connecting the divisions of the sleeve member, and the hinged division of said sleeve member being provided with a part normally arranged at one side 30 of the path of movement of the head of the clamping element and movable into said path when such movable division is swung outwardly on its hinge and thereby preventing detachment of the clamping element, 35 and a nut turning on the stem and the sections thereof against the projecting portions of the lugs, substantially as and for the purpose set forth.

22. In an electrical coupling, a body including a threaded stem and a transversely extending sleeve or band member at one end of the stem, portions of the stem adjoining the sleeve member comprising two part-cylindrical sections complementary to each 40 other, one being fixed to the major part of the stem and the other being separable therefrom, the fixed section of the stem including a part-cylindrical portion of opposite curvature to, and of less radius than, the threaded surface of such section, and the separable section being formed with a recess for receiving said part-cylindrical portion, and the portion of the sleeve member contiguous to said separable section being movable therewith, and a nut turning on the 45 stem and the sections thereof, substantially as and for the purpose described.

23. In an electrical coupling, a body including a threaded stem and a transversely extending sleeve or band member at one end of the stem, portions of the stem adjoining the sleeve member comprising two part-cylindrical sections complementary to each other, one being fixed to the major part of 55 the stem and the other being separable therefrom, the fixed section of the stem including a part-cylindrical portion of opposite curvature to, and of less radius than, the

threaded surface of such section, and the separable section being formed with a recess for receiving said part-cylindrical portion, and the portion of the sleeve member contiguous to said separable section being movable therewith, said stem being provided with an axial passage extending through the fixed section thereof and formed partly in the part-cylindrical portion of said fixed section and opening into the bore of the sleeve member, a movable clamping element having a head located within the bore of the sleeve member and a shank slidable in said passage, and a nut turning on the stem and the sections thereof and coacting with the clamping element, substantially as and for the purpose specified.

24. In an electrical coupling, a body including a threaded stem and a transversely extending sleeve or band member at one end of the stem, portions of the stem adjoining the sleeve member comprising two part-cylindrical sections complementary to each other, one being fixed to the major part of the stem and the other being separable therefrom, the fixed section of the stem including a part-cylindrical portion of opposite curvature to, and of less radius than, the threaded surface of such section, and the separable section being formed with a recess for receiving said part-cylindrical portion, said sections being formed with lengthwise recesses in their meeting faces opening through the peripheries of such sections into the bore of the sleeve member, the stem being provided with an axial passage extending through the fixed section thereof from the end face thereof and formed partly in the part-cylindrical portion of said fixed section and opening into the bore of the sleeve member and the sleeve member comprising two divisions, one being secured to said part-cylindrical section fixed to the major part of the stem and the other being hinged to the former division and movable on its hinge with the separable section of the stem, a movable clamping element having a head located within the bore of the sleeve member, a shank movable in the passage of the stem and lugs slidable in said recesses, the lugs projecting laterally beyond the periphery of the stem, the length of said element being greater than the distance from said end face of the stem to the hinge connecting the divisions of the sleeve member, and the hinged division of said sleeve member being provided with a part normally arranged at one side of the path of movement of the head of the clamping element and movable into said path when such movable division is swung outwardly on its hinge and thereby preventing detachment of the clamping element, and a nut turning on the stem and the

sections thereof against the projecting portions of the lugs, substantially as and for the purpose set forth.

In testimony whereof I, your petitioner,
5 JESSE L. HINDS, have hereunto signed my name in the presence of two attesting witnesses, at New York, in the county of New York, and in the State of New York, this 14th day of March, 1910, and I, your petitioner, JOHN J. DOSSERT, have hereunto signed my name in the presence of two attesting witnesses at Syracuse, in the county

of Onondaga, and in the State of New York, this 12th day of March, 1910.
